ATTORNEY.

UNITED STATES PATENT OFFICE.

ERLE H. HAND, OF BALTIMORE, MARYLAND.

SOUND-CONDUIT.

1,346,649.

Specification of Letters Patent.

Patented July 13, 1920.

Application filed November 5, 1919. Serial No. 335,836.

To all whom it may concern:

Be it known that I, ERLE H. HAND, a citizen of the United States, residing at Baltimore city, State of Maryland, have invented 5 certain new and useful Improvements in Sound-Conduits, of which the following is a specification.

This invention relates to talking machine tone arms, and its object is to provide a tone 10 arm with a means for so modifying the sounds issuing from the machine, that they are clear, mellow and penetrating.

The object stated is attained by means of a novel combination and arrangement of 15 parts to be hereinafter described and claimed, and in order that the same may be better understood, reference is had to the accompanying drawing forming a part of this specification.

20 In the drawing—

Figure 1 is a central longitudinal section of the device, and Fig. 2 is a cross-section on the line 2—2 of Fig. 1.

Referring specifically to the drawing, 5 25 denotes a fragment of the tone arm of a talking machine, the same leading to and opening into the throat of the usual horn or sound amplifier, which latter has not been shown, as it forms no part of the present invention. A fragment of the sound-conveying tube leading from the sound box is shown at 6. The sound box has also not been shown as it forms no part of the present invention. Ordinarily, the tube 6 is directly 30 35 connected to the tone arm 5, but in the present instance there is interposed between said parts a tone modifier which will now be described.

A tubular conduit has at one end 7 a 40 threaded or other suitable connection with the tube 6, and at the other end 8 with the tone arm 5. Intermediate its ends, the conduit is enlarged laterally to form an expansion chamber 9 which opens into the interior of the conduit. In order that the 45 chamber may be cut off more or less, or entirely from the interior of the conduit, there is mounted in the end 8 a sleeve 10. This sleeve is slidable in the conduit end 8 so 50 that it may be advanced across the chamber 9 as shown dotted in Fig. 1, in which position, the sleeve forms an uninterrupted continuation of the end 7 of the conduit and connects the latter directly with the end 8, 55 both ends of the sleeve being open.

It will be noted in Fig. 1 that the conduit

end 7 is slightly flared toward the chamber 9, and the internal diameter of the end 8 is slightly greater than that of the end 7, to accommodate the sleeve 10. It will also be 60 noted that the sleeve 10 is tapered in thickness in the direction of the part 5, so that when it is advanced to close the chamber 9, its interior will be flush with the interior of the ends 7 and 8 of the conduit. 65

For effecting the adjustment of the sleeve 10, a finger button 11 is attached thereto, the shank of the latter extending through a slot 12 in the part 8.

In front of the entrance end of the sleeve 70 10, or that end which is nearest to the part 7, hangs a gate 13 in the form of a flat circular plate or disk having a radially extending stem 14 by which it is loosely suspended from or pivotally connected to lugs 15 on the 75 inside of the chamber 9. The end of the sleeve 10 is behind the stem 14, and hence when the sleeve is advanced as hereinbefore described, to close the chamber 9, said end of the sleeve engages the stem and swings the 80 gate upwardly into the chamber, clear of the sleeve, and when the sleeve is pulled back to open the chamber, the gate drops back to its position in front of the sleeve end. It will be noted that the diameter of the gate 85 13 is less than the internal diameter of the sleeve 10, and hence when the gate is down, as shown in the drawing, it does not completely close the sleeve but leaves a sufficient space free and unobstructed for the passage 90 of the sound waves into the sleeve.

When the parts are in the position shown in Fig. 1, some of the sound waves passing through the part 7 toward the chamber 9, expand sidewise into the latter upon reaching 95 the same, whereby the sounds issuing from the instrument are rendered clear, mellow and penetrating, this effect being produced without choking or muffling. The gate 13 serves as a baffle, partially obstructing the 100 center of the sound passageway formed by the sleeve 10, and thereby directing the sound waves into the chamber 9 and along the wall of the sleeve subdued.

The sleeve 10 can be advanced more or 105 less across the chamber 9 to modify the tonal qualities of the instrument as may be desired, and it can also be set to completely close the chamber as shown dotted in Fig. 1, whereupon the passage of the sound waves 110 is in a straight line and without deflection laterally.

The preferred embodiment of the invention has been shown, but it will be understood that various changes and modifications may be made without a departure from the 5 spirit and scope of the invention as claimed hereinafter.

I claim:

1. A sound conduit having a section provided intermediate its ends with a lateral expansion chamber in communication with the interior thereof, a sleeve slidably mounted in one end of the section, and adjustable to extend across the chamber for shutting off the same from the interior of the section, and a 10 gate opposite that end of the sleeve into which the sound waves pass from the expansion chamber, said gate being dimensioned to partly close said end of the sleeve.
- 15 2. A talking machine tone arm having a

section provided intermediate its ends with a lateral expansion chamber in communication with the interior thereof, a sleeve slidably mounted in one end of the section, and adjustable to extend across the chamber for shutting off the same from the interior of the section, and a gate partly closing that end of the sleeve into which the sound waves pass from the expansion chamber, said gate being pivoted to the wall of the expansion chamber and engageable by the sleeve to swing into said chamber when the sleeve is advanced to close the latter.

In testimony whereof I affix my signature in the presence of two witnesses.

ERLE H. HAND.
